UNITED STATES PATENT OFFICE.

VLADIMIR POPOV, OF PILSEN, CZECHOSLOVAKIA.

MACHINE FOR PACKING BOXES.

Application filed June 15, 1926, Serial No. 116,213, and in Germany June 20, 1925.

The present invention relates to a machine for the packing of any desired materials into boxes consisting of one or two sheaths or coverings.

5 Packing machines, and particularly packing machines which co-operate with the machines that produce the articles to be packed (cigarettes for example) are required to be of large capacity. Thus for example one 10 packing machine must serve at least one cigarette machine, which makes more than one thousand cigarettes per minute. Existing packing machines (namely those which themselves receive the paper, make boxes out of 15 it, fill them with cigarettes, and close them with adhesive) do not permit of such a high capacity being attained, particularly when packing small quantities, such for example as five or ten articles in one packet or box. 20 The principal causes of the small capacity of existing packing machines are the following:—The drum-shaped revolving mechanisms employed in packing machines have an interrupted movement. After each rotation through a given angle the drum has to 25 be stopped, for the purpose of enabling the working movements necessary for producing a packet from a sheet of paper to be executed, and the packet produced on one shaping 30 body of the drum to be supplied for further treatment to a suitable piece of apparatus which receives the packet in a suitable sleeve or shell. In the case of such a method of working it is absolutely necessary for the 35 shaping body, by which the box is transferred to the sleeve, to take up an extremely accurate position in relation to the sleeve while the drum is stationary. The rotating 40 of the drum is executed with various devices, such for example as ratchet wheels and the like.

In the case of such mechanisms there arise at increased speeds centrifugal forces which make the stoppage of the drum in a definite 45 position impossible, for which reason the shaping bodies do not take up an accurate position in relation to the sleeves, as a result of which various disturbances occur which inevitably lead to the boxes being damaged 50 and torn.

By employing different kinds of pawls

with the ratchet wheels which would prevent the deviation of the drums from a particular position, the said disadvantage is not obviated since the positive stoppage of the drum in the required position is connected with shocks, for which reason the ratchet and pawl mechanism quickly wears out and the rotary mechanisms become impaired.

The disadvantages of existing packing 55 machines are completely obviated by the machine according to the present invention, and the essence of the invention consists in the fact that on a common shaft two drums are so secured that the moulds of the first drum, upon which the open boxes are manufactured, and the sleeves or shells of the second drum, which serve for the reception of the empty boxes made on the first drum, lie opposite to one another and execute the same 60 rotary movement jointly from one working position to the other. The correct position of the shaping bodies relative to the sleeves is ensured in the machine according to the present invention, independently of the 65 method of working of the driving mechanism.

A further disadvantage of existing packing 70 machines consists in the fact that their output is reduced by the opening of the boxes 75 in the transference thereof from the shaping bodies to the sleeves by the extruders. This opening is caused mainly by the fact that the adhesive by means of which the bottom of the box is struck down does not dry so 80 quickly as to prevent the boxes opening.

This defect is remedied in the machine according to the invention by a device, the object of which is to prevent the box from 85 opening during the operation of the extruder 90 which has a tendency to open the bottom of the box outwards from the inside, by a special finger or cam holding the box from outside during the extrusion period.

The further advantages of the machine 95 according to the present invention will be obvious from the further description.

The machine according to the invention is diagrammatically illustrated in the accompanying drawings:

Fig. 1 is a view from the front,

Fig. 2 a section on the line A—B in Fig. 1,

Fig. 3 a section on the line C—D in Fig. 2,
Fig. 4 a section on the line E—F in Fig. 2,
and

Fig. 5 a section on the line G—H in Fig. 1.
Fig. 6 is a diagram.

The object of the machine according to the invention is to pack various materials into boxes consisting of two sheaths or coverings, namely an inner sheath and an outer sheath.

10 In the drawings, 1 denotes a table upon which is secured a casing 2, which contains the actuating mechanisms. 3 is a flat casing or an actual plate in which also the actuating mechanisms are arranged. The 15 casing 3 is closed by a cover 4 (Fig. 2). Both the casings 2 and 3 serve as a superstructure for supporting the actual working members of the machine, which comprises three main constituents, namely a shaft 5, 20 and drums 6 and 7 secured thereto. The shaft 5, together with the drums 6 and 7, receives from the main shaft 8, which is set in rotation by the belt pulley 9 (Fig. 2) intermittent rotary movements, each amounting to 25 one-sixth of a revolution, and corresponding to the six working positions of the drums. This intermittent rotary movement may be produced by any desired known device, such for example as a pin 10 secured eccentrically to the main shaft 8, a rod 11, a 30 pawl 12, and a six-toothed ratchet wheel 13 (Fig. 3).

On the drum 6 are mounted six moulds 35 14^a, 14^b, 14^c, 14^d, 14^e, 14^f. In the interior of this drum are located the extruders 15^a, 15^b, 15^c, 15^d, 15^e, 15^f, which in consequence of the periodic rotation of the drum 6 come in turn into engagement with the rod 16 by means of teeth on the rear ends of the extruders 15^a to 15^f, the rod 16 likewise having teeth on its front end (Fig. 2). The moulds 14^a to 14^f, during one revolution of the drum 6, pass in succession through the 40 positions I, II, III, IV, V and VI (Fig. 6).

45 The drum 7 which is formed by a wheel is provided with six sleeves or shells 17^a, 17^b, 17^c, 17^d, 17^e, 17^f, which are arranged facing the moulds 14^a, 14^b, 14^c, 14^d, 14^e, and 14^f of the drum 6. The sleeves are secured to the 50 ends of shafts 18^a, 18^b, 18^c, 18^d, 18^e, and 18^f (see Figs. 2 and 5), the other ends of which carry plate-like drivers 19^a, 19^b, 19^c, 19^d, 19^e, and 19^f.

55 These drivers are located, in the positions I, II, III, IV, V, and VI, in grooves in a disc 20, which is secured to the plate 3 by means of a wedge or key and a nut 21, and which at the same time forms the bearing for the shaft 5, the hub of this disc constituting the pivot for a two-winged sector 22 (Figs. 1, 2 and 5). The driver, which from time to time takes up the position III, is located in the notch in a bevel wheel 27, which will be described hereinafter.

60 65 The lower vane of the sector 22 has pinion

teeth, which engage in the teeth of a lever 23, which can execute rocking movements on a shaft 24 by means of an eccentric groove on a toothed wheel 25, this toothed wheel admitting of being rotated by means of a toothed wheel 26 keyed on to the main shaft 8. For one revolution of the toothed wheel 26 the toothed wheel 25 only rotates through half a revolution, in order that for one revolution of the driving shaft the rocking movement of the lever 23 may only be executed towards one breadth. The lever 23 swings back during the following rotation of the working shaft. The rocking movements of the lever 23 are only executed when the drums 6 and 7 are stationary. During the revolution of the drums 7 and 6 the lever 23 must remain at rest, at the moment when the drums 6 and 7 are stationary and receiving interrupted motion from the main shaft 8 by means of the pin 10 (Fig. 3) fixed eccentrically to the axis of the shaft 8, the tension rod 11, the pawl 12 and the six-toothed ratchet wheel 13, an oscillation of the lever 23 takes place, caused by the shape of the eccentric curve of the toothed wheel 25, whereas during the revolving of the drums the pin of the lever 23 moves in those parts of the eccentric curve of the wheel 25 which are concentric with the centre line of rotation of the wheel 25, and the lever 23 can therefore perform no oscillation.

The rocking movement which the two-winged sectors 22 receives from the lever 23 is imparted by means of the upper wing of the sector 22, which is provided with bevel teeth, to the bevel wheel 27, which is rotatably arranged on a pin 28, which is secured in a notch in the pulley 20, the amplitude of the oscillating movement of the sector 22 being such that the toothed wheel 27 rotates through 180°. Since the toothed wheel 27 has a notch into which the driver 19^a to 19^f of the sleeve 17^a to 17^f penetrates when they are located just in the position III, the rotation of the toothed wheel 27 is likewise transmitted to the sleeve, so that all the sleeves that come into the position III are rotated through 180°.

The casing 3 contains rods 29, 30, 31, 32, and 33, which are placed as shown in Figure 2 and which have at their lower ends teeth in which engage teeth on the sectors 34, 35, 36, 37 and 38, which during a rotation of the working shaft, by means of the associated eccentrics, receive a rocking movement, which is imparted to the rods 29, 30, 31, 32, and 33, as a result of which these rods move up and down (Fig. 4).

Upon these rods are arranged folders for bending the paper round the moulds on the drum 6. The rod 29 has two folding devices for the bending over, and these consist of brackets 39 and 40, which have folding plates at their ends (Figs. 2 and 4). The rod 30

has likewise two brackets, 41 and 42. On the rod 31 are likewise located correspondingly curved brackets 43 and 44, upon which folding plates 45 and 46 are secured. The 5 rod 33 carries brackets 47 and 48 with flaps 49 and 50. The rod 32 imparts a movement, by means of the toothed wheels 51 and 52, to the shafts 53 and 54, bending devices 55 and 56, which are in the form of flat 10 hooks, being secured to these shafts.

The said rod 16, which is connected in turn with the extruders 15^a to 15^b by means of the hook-like teeth shown in Figure 2, as hereinbefore described, receives, at the time when 15 the drums 6 and 7 are stationary, from the working shaft 8, a reciprocating movement, in order that the latter may be transmitted to the associated extruders.

In Fig. 3 and in Fig. 2 is diagrammatically illustrated a transmission by means of which the rod 16 receives a movement from the working shaft 8, by means of a lever 57, a connecting rod 58, a rod 59 and toothed wheels 60 and 61, the last of which, through 25 a direct toothed connection, transmits the movement to the rod 16.

The rod 16 by means of screws or rivets and intermediate layers 62 is firmly connected by its rear end with a rod 63, which 30 consequently receives the same movements as the rod 16 and is guided in a guide 64 which is secured in a convenient manner to the wall of the casing 2.

At the front end of the rod 63 is located 35 a finger or cam 65, which under particular conditions can execute rocking movements on a pivot 66. In Fig. 2 the cam 65 assumes a position in which it cannot rotate about the pivot 66 as it is prevented from so doing by 40 a stop 67 on the left hand side, the determining influence of which resides in adjusting the finger 65 into the position shown in Fig. 2. The finger 65 cannot be rotated towards 45 the right as its front end bears upon the rod 63.

The mechanisms not hereinbefore described will be explained simultaneously with the description of the method of working of the machine.

In Fig. 3 the drum 6 is illustrated in that 50 position in which the mould 14^a takes up the position I and the mould 14^b the position IV. In this position there is placed above the mould 14^a on the table 68 a sheet of paper of suitable dimensions, which is to serve as the inner sheath of the box. This sheet of paper is represented in Fig. 3 by two lines. Under the mould 14^a is placed a sheet of paper, which serves as the outer sheath of 55 the box. In the manner already described the shaft 5 is further rotated at the same time with the drums through one-sixth of a revolution. The sheet of paper on the table 68 is seized by the mould 14^a, which in passing through a passage formed of two guid-

ing segments 70 and 71 bends over the paper at its edges into a channel shape. The mould 14^a, upon reaching the position II will therefore carry the paper in the condition shown in Fig. 6. At the same moment the 70 same working movement is also effected with the sheet of paper on the table 69. This sheet of paper passes, on the mould 14^a, through similar devices 69 and 72 before it passes out of the position IV into the position V.

The mould 14^a comes into the position II with the sheet of paper bent into a channel shape just in the same way as the mould 14^a comes out of the position IV into the position 80 V with the paper bent into a channel shape. In these positions the papers are further folded in a similar manner. The rod 33 is moved downwards by the sector 37 and imparts by means of the folding plate 50 to the 85 paper located on the mould 14^a a third longitudinally directed fold. The folding plate 49 of the rod 33 at the same time bends the outer paper sheath on the mould 14^a further over in its longitudinal direction. Hereupon the rod 33 with the folding plates 50 and 49 goes back and the rod 31 with the folding plates 46 and 45 moves upwards and carries out the fourth longitudinal bending 90 of the paper on the moulds 14^a and 14^b. 95 With the return of the rod 31 to the initial position the rod 32 begins to work and sets in motion the folding devices 55 and 56, which simultaneously carry out the first bending over of the end flaps projecting 100 above the mould, of the coverings located on the moulds 14^a and 14^b in the position II and the position V. Hereupon the drum executes a further sixth of a revolution, and by means of two stationary folding plates 105 75 and 76, which are secured to standards 73 and 74, during the rotation of the drum, the bending over of the second end flap of the box is carried out on the moulds 14^a and 14^b. 110 These moulds come in this manner into the positions III and VI, where two further folds are carried out, this being done by means of the rods 28 and of the folding devices 39 and 40 secured thereto, which carry out the third fold. The bending over 115 of the closing tip is executed by means of the rod 30 and of the folders 41 and 42.

It may be observed that in each position of rest of the drum 6 fresh sheets of paper must be placed on the tables 68 and 69, in 120 order that an uninterrupted working of the machine may be ensured.

The mould 14^a already covered with a sheet of paper, which it took in the position I from the table 68, comes into the position 125 IV, in which the outer sheet of paper is supplied. With this sheet the mould 14^a comes into the position V. On the way there the outer sheet is subjected to a preliminary folding, this being done in the manner already 130

described. In the position V the outer sheet receives two further longitudinal folds and an end fold. In the method of working already described the mould 14^a is exposed to 5 further working processes in the transition from the position V to the position VI, and finally the mould 14 comes back out of the position VI into the position I.

In the position I the finished box must be 10 brought by means of the extruder 15^a out of the mould 14^a into the associated sleeve or shell 17^a on the drum 7. Since in the event of such a displacement of the box, the bottom thereof would be opened by the extruder 15^a, it is necessary to prevent such opening 15 from occurring. For this purpose, in front of the box, is arranged a finger or cam 65, already described, which during the movement of the box out of the mould 14^a or the 20 like on the drum 6 into the sleeve or shell 17^a or the like on the drum 7 moves in front of the box and keeps the end of the box closed, and does not quit the holding position in front of the box even when the same already 25 moves into the sleeve, for which purpose the sleeves have corresponding slots (see Figs. 1 and 3) which enable the finger to maintain its operative position.

As soon as the box takes up its position in 30 a sleeve on the drum 7 the finger 65 must be brought out of the operative position, that is to say its free end, which keeps the bottom of the box closed forwardly during the working stroke, must be displaced side-ways (see Fig. 35 2). This displacement is effected in the following manner:—The finger 65, which has traversed the slots in the corresponding sleeves, strikes at the end of its travel against the wall of a receiving channel 77, which con- 40 strains the finger 65 to rotate about the pin 66, so that it takes up a position parallel to the rod 63, in which position the finger is guided back into its original position without touching the box supported in the corre- 45 sponding sleeve. During its rearward travel the finger 65 strikes against the stop 67 and is thereby rotated back afresh about the pin 66 into the working position.

In this manner as may be seen from the 50 description of the method of working for the manufacture of boxes on the drum 6, each time the drum is stationary completely similar working processes are executed in the positions located opposite to one another, 55 as well as during the transition from one position to the next. In the position I the box consisting of two paper sheaths, comes by means of the combined method of working of the extruders and of the finger 65 in- 60 to a corresponding sleeve on the drum 7. During a rotation of the drum this box with its sleeve comes into the position II, as has already been mentioned, the sleeve in the position II, in consequence of the rotation of 65 the bevel wheel 27 through 180°, is rotated

transversely to its longitudinal axis, and therefore the box, which arrived in the position II with its open end at the back, now rotates in such a way that its open end comes to the front in order that the material to be packed may be able to be introduced into the box.

From the position II the box is brought 70 into the position III and then further into the position IV. In one of these positions the box is filled in a suitable manner with the material to be packed, such as cigarettes for example. Out of the position IV the filled 75 box comes into the position V, where by means of the drop levers 78 and 79, illustrated in Figure 1, which are connected with one another by teeth and are set going by the associated eccentrics on the working shaft 8 by means of the lever 80 and the connecting rod 81, the bending over of the two short end flaps of the box is carried out.

During the passing of the box from the position V into the position VI a third fold is produced at the end of the box by means of a bending template 82, which is secured 80 to the standard 83. During the passing out of the position VI into the position I the final closing of the box is effected by means of the template 84 fitted on to the standard 85.

Since in the position I, in the sleeve 17^a a 90 finished box is located, and out of the mould 14^a, as already mentioned, into the said sleeve 17^a out of the drum 6 a finished empty box is introduced, the procedure of transferring 100 a box from the drum 6 to the drum 7 is modified as follows:—The box which has been pushed out of the mould 14^a by the extruder 15^a, and which is held in front by the finger 65, meets in the sleeve 17^a with the finished 105 full box, the finger 65 first of all meeting this full box and in this manner finding a resistance on the full box and being pressed away to one side, so that the bottom of the empty box coming out of the mould 14^a into the sleeve 17^a is no longer held by the finger 65, but bears against the end of the finished 110 full box which is still located in the sleeve 17^a.

As soon as the sleeves of the drum 7 begin 115 to deliver finished boxes in the position I, the finger 65 guides the boxes coming out of the moulds of the drum 6 into the sleeves of the drum 7 only until these fresh boxes touch the finished full boxes, the further forward movement of the finger 65 being effected in a position parallel to the rod 63. In this condition the finger 65 returns to its original position in which it passes by the boxes and here assumes afresh 120 by means of the stop 67 its working position for the next working stroke.

Hence the sleeves rotate, after they have 125 obtained possession in the position I of the boxes supplied, in one of the following posi-

tions through 180°, and in this rotated condition they come back into the position I after having traversed all the other positions. The boxes out of the first drum 6 therefore 5 enter the sleeves on one side and on the other side alternately.

What I claim is:—

1. A machine for packing materials or articles into boxes each consisting of an inner sheath and an outer sheath, comprising a rotatable shaft, two drums secured to said shaft, a number of moulds for the formation of boxes, secured to the first of said drums, and an equal number of sleeves for the reception of said boxes secured to the second of said drums, each sleeve on the second drum remaining at all times opposite to one and the same mould on the first drum. 10
2. A machine for packing materials or articles into boxes each consisting of an inner sheath and an outer sheath, comprising a rotatable shaft, two drums secured to said shaft, an even number of moulds for the formation of boxes secured to the first of said drums, an equal number of sleeves for the reception of said boxes secured to the second of said drums, each sleeve on the second drum remaining at all times opposite to one and the same mould on the first drum, and means for rotating each sleeve through half a revolution when it reaches one particular working position, so that partially formed boxes reaching that position with their open ends 15 at the back have their open ends brought to the front. 20
3. A machine for packing materials or articles into boxes each consisting of an inner sheath and an outer sheath, comprising a rotatable shaft, two drums secured to said shaft, a number of moulds for the formation of boxes, secured to the first of said drums, an equal number of sleeves for the reception of said boxes secured to the second of said drums, each sleeve on the second drum remaining at all times opposite to one and the same mould on the first drum, half the moulds being adapted to form the inner sheaths of boxes and the other half being adapted to form outer sheaths, and two similar sets of diametrically opposite folding devices adapted to 25 form all the longitudinal and bottom folds required for the production of inner sheaths and outer sheaths respectively at diametrically opposite positions on the first drum. 30
4. A machine for packing materials or articles into boxes each consisting of an inner sheath and an outer sheath, comprising a rotatable shaft, two drums secured to said shaft, a number of moulds for the formation of boxes, secured to the first of said drums, an equal number of sleeves for the reception of said boxes secured to the second of said drums, each sleeve on the second drum remaining at all times opposite to one and the same mould on the first drum, extruders adapted to push boxes out of the moulds on the first drum and into the sleeves on the second drum, and means for preventing said extruders from opening the boxes. 35
5. A machine for packing materials or articles into boxes each consisting of an inner sheath and an outer sheath, comprising a rotatable shaft, two drums secured to said shaft, a number of moulds for the formation of boxes, secured to the first of said drums, an equal number of sleeves for the reception of said boxes secured to the second of said drums, each sleeve on the second drum remaining at all times opposite to one and the same mould on the first drum, extruders 40
6. A machine for packing materials or articles into boxes each consisting of an inner sheath and an outer sheath, comprising a rotatable shaft, two drums secured to said shaft, an even number of moulds for the formation of boxes secured to the first of said drums, an equal number of sleeves for the reception of said boxes secured to the second of said drums, each sleeve on the second drum remaining at all times opposite to one and the same mould on the first drum, half the moulds being adapted to form the inner sheaths of boxes and the other half being adapted to form outer sheaths, two similar sets of diametrically opposite folding devices adapted to form all the longitudinal and bottom folds required for the production of inner sheaths and outer sheaths respectively 45 at diametrically opposite positions on the first drum, extruders adapted to push boxes out of the moulds on the first drum and into the sleeves on the second drum, and means for preventing said extruders from opening the boxes. 50
7. A machine for packing materials or articles into boxes each consisting of an inner sheath and an outer sheath, comprising a rotatable shaft, two drums secured to said shaft, an even number of moulds for the formation of boxes secured to the first of said drums, an equal number of sleeves for the reception of said boxes secured to the second of said drums, each sleeve on the sec- 55

ond drum remaining at all times opposite to one and the same mould on the first drum, half the moulds being adapted to form the inner sheaths of boxes and the other half being adapted to form outer sheaths, two similar sets of diametrically opposite folding devices adapted to form all the longitudinal and bottom folds required for the production of inner sheaths and outer sheaths respectively at diametrically opposite positions on the first drum, extruders adapted to push boxes out of the moulds on the first drum and into the sleeves on the second drum, a rod virtually integral with each extruder, a finger pivoted to the front end of said rod, the free end of the finger being adapted to bear against the closed bottom of the box that is being transferred by the extruder, means for rocking the pivoted finger into a position in which it will not touch a box during the return movement of the rod, and a stop adapted to engage with the pivoted finger at the end of the return movement of the rod and rock it back again into a position in which it can bear against the closed bottom of a box.

8. A machine for packing materials or articles into boxes each consisting of an inner sheath and an outer sheath, comprising a rotatable shaft, two drums secured to said shaft, an even number of moulds for the formation of boxes secured to the first of said drums, an equal number of sleeves for the reception of said boxes secured to the second of said drums, each sleeve on the second drum remaining at all times opposite to one and the same mould on the first drum, half the moulds being adapted to form the inner sheaths of boxes and the other half being adapted to form outer sheaths, two similar sets of diametrically opposite folding devices adapted to form all the longitudinal and bottom folds required for the production of inner sheaths and outer sheaths respectively at diametrically opposite positions on the first drum, and means for rotating each sleeve through half a revolution when it reaches one particular working position, so that partially formed boxes reaching that position with their open ends at the back have their open ends brought to the front.

9. A machine for packing materials or articles into boxes each consisting of an inner sheath and an outer sheath, comprising a rotatable shaft, two drums secured to said shaft, a number of moulds for the formation of boxes, secured to the first of said drums, an equal number of sleeves for the reception of said boxes secured to the second of said drums, each sleeve on the second drum remaining at all times opposite to one and the same mould on the first drum, extruders adapted to push boxes out of the moulds on the first drum and into the sleeves on the second drum, means for preventing

said extruders from opening the boxes, and means for rotating each sleeve through half a revolution when it reaches one particular working position, so that partially formed boxes reaching that position with their open ends at the back have their open ends brought to the front. 70

10. A machine for packing materials or articles into boxes each consisting of an inner sheath and an outer sheath, comprising a rotatable shaft, two drums secured to said shaft, a number of moulds for the formation of boxes secured to the first of said drums, an equal number of sleeves for the reception of said boxes secured to the second of said drums, each sleeve on the second drum remaining at all times opposite to one and the same mould on the first drum, extruders adapted to push boxes out of the moulds on the first drum and into the sleeves 75 on the second drum, a rod virtually integral with each extruder, a finger pivoted to the front end of said rod, the free end of the finger being adapted to bear against the closed bottom of the box that is being transferred by the extruder, means for rocking the pivoted finger into a position in which it will not touch a box during the return movement of the rod, a stop adapted to engage with the pivoted finger at the end 80 of the return movement of the rod and rock it back again into a position in which it can bear against the closed bottom of a box, and means for rotating each sleeve through half a revolution when it reaches one particular working position, so that partially formed boxes reaching that position with their open ends at the back have their open 85 ends brought to the front. 90

11. A machine for packing materials or articles into boxes each consisting of an inner sheath and an outer sheath, comprising a rotatable shaft, two drums secured to said shaft, an even number of moulds for the formation of boxes secured to the first of said drums, an equal number of sleeves for the reception of said boxes secured to the second of said drums, each sleeve on the second drum remaining at all times opposite to one and the same mould on the first 100 drum, half the moulds being adapted to form the inner sheaths of boxes and the other half being adapted to form outer sheaths, two similar sets of diametrically opposite folding devices adapted to form all 105 the longitudinal and bottom folds required for the production of inner sheaths and outer sheaths respectively at diametrically opposite positions on the first drum, extruders adapted to push boxes out of the moulds on the first drum and into the sleeves 110 on the second drum, a rod virtually integral with each extruder, a finger pivoted to the front end of said rod, the free end of the finger being adapted to bear against the 115 120 125 130

closed bottom of the box that is being transferred by the extruder, means for rocking the pivoted finger into a position in which it will not touch a box during the return movement of the rod, a stop adapted to engage with the pivoted finger at the end of the return movement of the rod and rock it back again into a position in which it can bear against the closed bottom of a box,

and means for rotating each sleeve through 10 half a revolution when it reaches one particular working position, so that partially formed boxes reaching that position with their open ends at the back have their open ends brought to the front.

In testimony whereof I have signed my name to this specification.

VLADIMIR POPOV.
